UNITED STATES PATENT OFFICE.

PERCY RILEY, OF COVENTRY, ENGLAND.

INTERNAL-COMBUSTION ENGINE.

1,148,052.

Specification of Letters Patent. Patented July 27, 1915.

Application filed October 29, 1909. Serial No. 525,321.

To all whom it may concern:

Be it known that I, PERCY RILEY, engineer, a subject of the King of Great Britain, residing at Hollybank, Radford Road, Coventry, Warwickshire, England, have invented new and useful Improvements in Internal-Combustion Engines, of which the following is a specification.

This invention relates to internal combustion engines having one or more cylindrical slide valves co-axial with the cylinder.

Engines having two cylindrical slide valves and a piston working directly within them are now on the market and it is found that difficulties occur owing to the heating and expansion of the slide valves and to the thrust of the piston on the inner slide valve. For in this engine the heat generated by combustion has to pass through three thicknesses of metal and two of oil before reaching the cooling fluid, the slide valves therefore become highly heated while the inner valve owing to its becoming the hottest expands more than the outer one often causing the slide valves to bind. Moreover as the piston works in a moving slide valve its thrust tends to force the slide valve in its direction of movement which thrust has to be taken by the eccentric shaft. In this engine also lubrication is very difficult especially that of the top rings of the inner slide valve as the flame and the hot gases come in contact with practically all the inner surface of the slide valve.

According to this invention a fixed cylinder in which the piston works has one or more cylindrical slide valves arranged co-axial with and outside it and a second cylinder or casing may be provided outside the slide valve or valves both cylinders being preferably water jacketed in order that the slide valve may be cooled on both sides.

In the drawings:—Figure 1 is a vertical section of a cylinder of an engine having two slide valves constructed according to this invention. Fig. 2 is an elevation showing the slide valves and operating mechanism of a four cylinder engine. Fig. 3 is a plan of Fig. 2. Figs. 4 and 5 are elevations of the slide valves shown in Fig. 1. Fig. 6 is a vertical section of a cylinder of an engine having a single slide valve constructed according to this invention. Fig. 7 is a similar view of a modification in which a cylindrical casing for the valve is provided

which is made integral with the engine cylinder.

Referring to Fig. 1, the cylinder 1 having inlet and outlet ports 2 and 3 has a head 4 and is fixed to the crank case 5 by means of the second cylinder or casing 6. The casing is formed with inlet and outlet ports 7 and 8 in line with the ports 2 and 3 in the fixed cylinder 1. The cylinders 1 and 6 are water jacketed at 9 and 10 respectively. Co-axial with the fixed cylinder 1 and outside it are the two slide valves 11 and 12, the slide valve 11 having two ports or series of ports 13 and 13 and the slide valve 12 having similarly two ports or series of ports 14, 15 adapted to cover and uncover the inlet ports 2, 7 and outlet ports 3, 8 at the proper time in the usual manner in this type of engine. It will be seen that the valves 11, 12 work between two water cooled surfaces while the piston 16 is also water cooled, making this system suitable for engines of large as well as of small cylinder diameter.

The water jacket 10 may be dispensed with the casing being cooled by air in which case it is preferably provided with radiating fins. The casing 6 may also be partly cut away for the sake of lightness if desired.

The mechanism for operating the slide valves is as follows:—The slide valves 11 and 12 have each two flanges at the bottom, and are cut away as shown. Rocking levers 17, 18, 19, 20, 21, 22 pivoted on shafts 23 have pins 24 which engage with the flanges of the slide valves the other ends of the rocking levers 17, 18, 20, 21, being connected by links 25, 26, 27, 28, terminating in eccentric straps 29, 30, 31, 32 working upon eccentrics 33, 34, 35, 36 set at the required angle in relation to one another on the half time shaft. The rocking levers 17 and 19 are connected together by a link 27 while the rocking levers 20, 22 are similarly connected by the link 38.

It will be seen that each eccentric moves one slide valve of two of the cylinders in opposite directions and therefore in engines having an even number of cylinders the number of eccentrics will be equal to half the number of the slide valves. For instance the eccentric 34 operates a slide valve of each of the two inner cylinders through the rocking lever 18 and link 26; the eccentric 33 operates a slide valve of each of the outer cylinders through the rocking levers

17, 19 and links 25 and 37. Similarly the eccentrics 35, 36 each operate two slide valves.

In Fig. 6 a modification is shown in which 5 a cylindrical slide valve 11^a is employed. In this construction the cylinder 1^a, cylinder head 4^a, crank casing 5^a, and water jacket 9^a are substantially similar to those shown in Fig. 1. The ports 2^a, 7^a, 3^a and 8^a are also 10 similar to the ports 2, 7, 3, and 8 before described. The admission and exhaust ports 13^a, 13^b are in different planes and are suitably arranged to operate in the usual way. It will be observed that there is no outer 15 water jacket for the valve but that the piston 16^a operates in a stationary water jacketed cylinder with which the valve 11^a is coaxial.

In Fig. 7 a single cylindrical slide valve 20 11^c is shown and the cylinder 1^c, cylinder head 4^c, crank casing 5^c, water space 9^c, piston 16^c, and the ports 2^c, 7^c, 3^c, 8^c, 13^c and 13^d are similar to those shown in Fig. 6, but in this case the cylindrical valve 11^c is 25 closed in a cylindrical casing 100 which is formed integrally with the cylinder head 4^c and also with the upper part of the crank casing 5^c.

What I claim is:—

30 1. In a four cycle internal combustion engine a fixed cylinder having lateral inlet and exhaust ports, cylindrical port controlling means of the sleeve valve type rigid against internal pressure, coaxial with and outside the cylinder, and controlling both the inlet and exhaust ports, a piston in the fixed cylinder, and mechanism whereby the valve controlling means is moved to close the cylinder ports during the compression and explosion cycles of the engine.

2. In a four cycle internal combustion engine a fixed cylinder having lateral inlet and exhaust ports, cylindrical port-controlling means of the sleeve valve type rigid against 45 internal pressure, coaxial with and outside the cylinder and controlling both the inlet and exhaust ports, means for cooling the fixed cylinder within the cylindrical port-controlling means, a piston in the fixed 50 cylinder and means whereby the port-controlling means is moved to close the cylinder ports during the compression and explosion cycles of the engine.

3. In a four cycle internal combustion engine, a fixed cylinder having lateral inlet and exhaust ports, cylindrical port-controlling means of the sleeve valve type rigid against internal pressure, coaxial with and outside the cylinder and controlling both 55 the inlet and exhaust ports, a cylindrical casing outside the port-controlling means for cooling the cylindrical casing outside the port-controlling means, a piston in the fixed cylinder and means whereby the port-controlling means is moved to close the cylinder

ports during the compression and explosion cycles of the engine.

4. In a four cycle internal combustion engine a fixed cylinder having lateral inlet and exhaust ports, cylindrical port-controlling 70 means of the sleeve valve type rigid against internal pressure, coaxial with and outside the cylinder and controlling both the inlet and exhaust ports, a cylindrical casing outside the port-controlling means, means for cooling 75 the fixed cylinder within the port-controlling means and the cylindrical casing outside said port-controlling means, a piston in the fixed cylinder and means whereby the port-controlling means is moved to close the cylinder ports during the compression and 80 explosion cycles of the engine.

5. In an internal combustion engine, a fixed cylinder ported for admission and exhaust, cylindrical slide valves rigid against 85 internal pressure sliding one within the other coaxial with and outside the cylinder, a piston within the fixed cylinder and means whereby the valves are moved to close the cylinder against admission or exhaust during 90 the compression and explosion cycles of the engine.

6. In an internal combustion engine, a fixed cylinder ported for admission and exhaust, cylindrical slide valves rigid against 95 internal pressure sliding one within the other coaxial with and outside the cylinder, means for cooling the fixed cylinder within the cylindrical valves, a piston within the fixed cylinder, and means whereby the valves 100 are moved to close the cylinder against admission or exhaust during the compression and explosion cycles of the engine.

7. In an internal combustion engine, a fixed cylinder ported for admission and exhaust, cylindrical slide valves rigid against 105 internal pressure sliding one within the other coaxial with and outside the cylinder, a cylindrical casing outside the slide valves, means for cooling the cylindrical casing outside the slide valves, a piston within the fixed cylinder, and means whereby the valves 110 are moved to close the cylinder against admission or exhaust during the compression and explosion cycles of the engine.

8. In an internal combustion engine, a fixed cylinder ported for admission and exhaust, cylindrical slide valves rigid against 115 internal pressure sliding one within the other coaxial with and outside the cylinder, a cylindrical casing outside the slide valves, means for cooling the fixed cylinder within the cylindrical valves and the cylindrical casing outside the valves, a piston within the fixed cylinder and means whereby the 120 valves are moved to close the cylinder against admission or exhaust during the compression and explosion cycles of the engine.

9. In an internal combustion engine, an 130

even number of fixed cylinders, cylindrical slide valves co-axial with and outside the cylinders, pistons within the cylinders, rocking levers, means for connecting the rocking levers to the slide valves, eccentrics and links connecting the eccentrics and rocking levers so that each eccentric moves two slide valves in opposite directions.

10. In an internal combustion engine, an even number of fixed cylinders, cylindrical slide valves co-axial with and outside the cylinders, pistons within the cylinders, rocking levers, flanges on the slide valves, means for connecting the flanges to the rocking levers, eccentrics and links connecting the eccentrics and rocking levers so that each

eccentric moves two slide valves in opposite directions.

11. In an internal combustion engine, an even number of fixed cylinders, cylindrical slide valves co-axial with and outside the cylinders, pistons within the cylinders, rocking levers, means for connecting the rocking levers and the slide valves, half the number of eccentrics as there are slide valves, and links connecting the eccentrics to the rocking levers.
